UNITED STATES PATENT OFFICE.

LEON SCHAEFFER, OF BROOKLYN, NEW YORK.

FLYING MACHINE.

Application filed June 8, 1921. Serial No. 475,908.

To all whom it may concern:

Be it known that I, LEON SCHAEFFER, a citizen of the United States, and a resident of New York, borough of Brooklyn, in the county of Kings and State of New York, have invented certain new and useful Improvements in a Flying Machine, of which the following is a full, clear, and exact specification.

- 10 This invention relates more particularly to a class of aeroplanes.
 My invention has for its object primarily to provide a flying machine or aeroplane adapted to be employed for carrying persons in the air, and which is of a type whereby the machine may be so operated that it will rise directly or rise on such an incline from its landing that the requirement for driving it considerable distance 15 on the landing to take the customary gradual climb will be avoided, the machine also being driven by pairs of propellers, in order to obtain unusual speed, besides serving to prevent tendency of the machine from shifting to dangerous lateral inclines when moving through the air. The invention consists 20 essentially of rotatably mounting on a flying machine of a suitable type one or more propellers adapted to be driven for lifting the machine in the air from its landing, and 25 also mounted on the ship may be one pair or a number of pairs of propellers adapted to be operated in unison for driving the machine. The propellers for raising the machine 30 are first driven independently at a high speed and when the machine is elevated to a desired height the driving propellers are operated, all these propellers being driven by mechanism operated by the engine 35 of the machine. The mechanism has separately operable parts so that when the driving propellers are driven the speed of the raising propellers may be reduced to prevent tendency to retard the forward movement of the machine while still serving to assist in maintaining the machine in the air. 40 Associated with the mechanism is a controller or switch which is manually adjustable for causing each part of the mechanism 45 to be cut-in and cut-out of operation by the engine.
 50

A further object of the invention is to provide a flying machine of a simple, efficient and durable construction.

55 With these and other objects in view, the

invention will be hereinafter more particularly described with reference to the accompanying drawings forming a part of this specification in which similar characters of reference indicate corresponding parts in all the views, and will then be pointed out in the claims at the end of the description.

In the drawings, Figure 1 is a top plan, partly broken away, of one form of flying machine embodying my invention.

Fig. 2 is an enlarged elevation of the machine, partly broken away and partly fragmentary, with the fuselage removed therefrom.

Fig. 3 is an enlarged top plan, partly fragmentary, of the mechanism employed in the machine in conjunction with the engine.

Fig. 4 is an enlarged plan of one of the propellers used for raising the machine.

Fig. 5 is an enlarged end view of one of the propellers used for driving the machine.

Fig. 6 is an enlarged end view of one of the steering propellers employed on the machine, and

Fig. 7 is an elevation of the steering propeller.

The machine may be in the form of an aeroplane of the usual or any preferred type having a fuselage 10, one or two planes, as 11, 12, and at the rear of the machine may be the usual tail, as 13, while interiorly of the fuselage may be provided any suitable make of engine, as 13^a, for driving the machine through the air.

When the machine is provided with the two spaced superimposed planes 11 and 12 in the end parts of the upper plane 12 are journaled two vertically disposed shafts, as 14 and 15, both of which are of lengths so that their lower ends extend in proximity to the lower plane 11, while the upper ends of the shafts extend considerable distances above the upper plane. On the parts of each of the shafts 14 and 15 above the plane 12 may be one or a number of propellers 16, 16^a, 16^b. These propellers are of sizes and their blades are arranged for serving when revolved to cause the machine to be raised from its landing, and on the lower ends of the shafts 14 and 15 are bevel gears 17 and 17^a.

In the forward end part of the fuselage 10 is journaled a shaft 18 having its ends extending laterally from the sides of the fuselage, and on the protruding ends of this

shaft are held a pair of propellers 19 and 20. In the rear end part of the fuselage is journaled a shaft 21 having its ends projecting also laterally from the sides of the fuselage, and on the extending ends of the shaft 21 are held another pair of propellers 22 and 23. The pairs of propellers 19, 20 and 22, 23 are of sizes as well as being of forms adapted to propel the machine forward where revolved.

Above the central part of the fuselage 10 may be rotatably mounted a shaft 24 on which is held a propeller 25 of a form adapted when driven to cause the machine to travel rearwardly. All of the propellers are adapted to be driven by the engine of the machine through the medium of a common mechanism, as 26.

The mechanism 26 may be of any suitable type, though the form illustrated includes a main drive shaft 27 and an auxiliary drive shaft 28. The main shaft 27 is driven direct by the engine 14, and this shaft is vertically disposed as well as being of a length so that it extends above the fuselage 10 and above the plane 11. On the upper end of the main shaft is a bevel gear 29, and in mesh with this gear is a bevel gear 30 held on one end of the auxiliary drive shaft 28 which is journaled in a bearing 30^a provided so that the auxiliary shaft is longitudinally disposed. The bevel gears 29 and 30 are of corresponding sizes so that the speed of the auxiliary shaft will be the same as the speed of the main shaft when driven. On the central part of the auxiliary shaft 28 is a large gear 31, and on the second end of this shaft is a wide gear or pinion 32. In spaced relation to the auxiliary shaft 28 is a longitudinally disposed shaft 33 which is journaled in one or more bearings 34, and this shaft is of a length so that it extends from spaced proximity to the bevel gear 29 of the main drive shaft 27 to close proximity to the bevel gear 17 of the vertical shaft 14 of the raising propellers. On one end of the shaft 33 is held a bevel gear 35 which meshes with the bevel gear 16 of the shaft 14, and on the second end of this shaft 33 is a gear 36 meshing with a gear 37 held on one end of a longitudinally disposed shaft 38 which extends in close proximity to the vertical shaft 15. The longitudinal shaft 38 is journaled in one or more bearings 39, and also on this shaft is a bevel gear 40 which is in mesh with the bevel gear 17^a of the vertical shaft 15. Slidably keyed on the central part of the shaft 33 is a pinion 41 and a large gear 42 which is of a diameter preferably corresponding to the diameter of the gear 31 of the auxiliary shaft 28. The pinion 41 is adapted to be moved into and out of mesh with the large gear 31 of the auxiliary shaft 28, and the large gear 42 is adapted to be moved into and out of mesh with the wide gear 32 of the auxiliary

shaft, the gear 42 being approximately one-half the width of the gear 32. Journaled in a bearing 43 is a shaft 44 which is in spaced relation to the shaft 33, and on one end of the shaft 44 is a sprocket 45. The sprocket 45 carries a sprocket chain 46 which also passes over a sprocket 47 held on a short shaft 48 which is journaled in the forward part of the fuselage 10, and also on the shaft 48 are two grooved pulleys 49 and 50. On the shaft 18 of the pair of driving propellers 19 and 20 is a pulley 51, and over this pulley as well as over the pulley 49 passes a belt 52. On the shaft 21 of the driving propellers 22 and 23 is a pulley 53 and passing over this pulley and over the pulley 50 is a belt 54. On the shaft 44 is held a gear 55 which is of a diameter corresponding to the diameter of the wide gear 32, and the gear 55 is also approximately one-half the width of the gear 32. The gears 32 and 55 are spaced apart sufficient distance so that the large gear 42 may be moved into mesh with both of the gears 32 and 55 at the same time. Journaled in a bearing 56 is a shaft 57 which is spaced below the shaft 33 and under the pinion 40 and gear 42. On one end of the shaft 57 is a gear 58 which is one-half the width of the gear 32 as well as being on alignment with one-half of the gear 32 so that the large gear 42 of the shaft 33 may be adjustably moved first into mesh with the gear 55 and with one-half of the gear 32, after which the gear 42 may be moved into mesh with the other half of the gear 32 and into mesh at the same time with the gear 58. At the other end of the shaft 57 is a pulley 59, and on the shaft 24 of the propeller 25 is a pulley 60. Passing over the pulleys 59 and 60 is a belt 61, and by this arrangement when the gear 42 is moved into mesh with the gear 58 and with the second half of the gear 32 the part of the mechanism which drives the machine forward will be cut-out, and the propeller 25 will be driven to cause the machine to travel rearwardly, as will be hereinafter more fully explained.

The gear 31 of the auxiliary shaft 28 with the gear 42 of the shaft 33 serve as drive gears, and the other gears and pinions of the mechanism are proportioned relative to these drive gears that the sets of raising propellers 16, 16^a, 16^b will first be driven at a high speed, then reduced in speed with the subsequent driving of the pairs of propellers 19, 20 and 22, 23. In order to permit the pinion 41 and drive gear 42 to be adjustably moved on the shaft 33 for causing the parts of the mechanism 26 to be cut-in and cut-out a controller 62 is provided. The controller 62 may be in the form of a bar or lever having one of its ends pivotally held in any well known manner to a sleeve 63 which is attached to the pinion 41 and gear 42 so that this sleeve, the pinion 41 and gear 42 may

revolve with the rotation of the shaft 33 without revolving the lever.

To start the machine in motion from its landing the controller or lever 62 is manually shifted for causing the pinion 41 to mesh with the drive gear 31 after starting the engine 13^a for driving the main shaft 27. The rotation of the main shaft with driving of the bevel gear 29 will be imparted to the bevel gear 30, auxiliary shaft 28, wide gear 32 and drive gear 31. The rotation of the drive gear 31 will then be imparted to the pinion 41, shaft 33, drive gear 42 and gear 36. The gear 36 will drive the pinion 37, shaft 38, and with the rotation of the shafts 33 and 38 in unison the bevel gears 35 and 40 of these shafts will revolve the bevel gears 17 and 17^a for driving the vertical shafts 14 and 15. Both sets of the propellers 16, 16^a, 16^b will thereby be driven at a high speed for causing the machine to rise in the air to a suitable height. The machine is then operated to travel forwardly by shifting the controller 62, pinion 41 and drive gear 42 on the shaft 33 so that the pinion is out of mesh with the drive gear 31 and so that the gear 42 is in mesh with one-half of the wide gear 32 and with the gear 55. The rotation of the main shaft 27 will then be imparted to the bevel gears 29 and 30, auxiliary shaft 28, gear 31, wide gear 32, drive gear 42 and gear 55 which in turn will revolve the shaft 44, sprocket 45, sprocket chain 46, sprocket 47, shaft 48, pulleys 49 and 50, belts 52 and 54, pulleys 51 and 53, shafts 18 and 21, and both pairs of the propellers 19, 20 and 22, 23, will be simultaneously driven. The gear 55 being considerably smaller than the gear 42 these parts of the mechanism for driving the propellers 19, 20 and 22, 23 will be operated at a high speed for causing fast forward travel of the machine, and the speed of the sets of the raising propellers 16, 16^a, 16^b will be reduced by reason of freeing the engagement of the pinion 41 with the drive gear 31, the gear 32 being relatively smaller than the gear 42 to accomplish the required reduction of the speed of the raising propellers, in order to assist in maintaining the machine in the air as well as tending to avoid possible lateral tilting of the machine. When it is desired to stop the forward travel of the machine and cause it to travel rearwardly, the controller 62 is adjusted to shift the drive gear 42 into mesh with the second half of the wide gear 32 and with the gear 58 of the shaft 57. The operation of the main shaft 27 of the engine will then be imparted to the bevel gears 29 and 30, auxiliary shaft 28, gear 31, wide gear 32, drive shaft 42, gear 58, shaft 57, pulley 59, belt 61, pulley 60, and shaft 24 for driving the propeller 25 in a direction to cause rearward travel of the machine. To enable the machine to make a safe landing the engine is operated so that the parts of the mechanism 26 will drive sets of the propellers 16, 16^a, 16^b at a speed for taking the air to counter-balance in part the weight of the machine, in order that it will descend gradually, the operation of the driving propellers 19, 20, 22, 23 being slowed or stopped entirely according to the requirement for making either a gradual or a direct descent. Encircling the fuselage 10 may be a chamber, as 63^a, in the form of a continuous pipe or shell for being filled with gas or air through the valve, as 63^b, to sufficiently offset the weight of the machine so that it will tend to readily rise in the air when the sets of the propellers 16, 16^a, 16^b are driven as well as serving to assist in permitting the machine to be maintained afloat in the air.

At the rear of the machine may be provided an apparatus, as 64, to allow the machine to be steered in right and left directions when desired. The apparatus 64 consists preferably of two spaced shafts 65 and 66 which are journaled in vertical positions at the rear end of the fuselage 10, and on these shafts are propellers or rudders, as 67 and 68, Figs. 1, 6, 7. Each of these rudders may be composed of a hub 69 from which is disposed in triangular arrangement three spaced similarly curved blades, as 70, 70^a, 70^b, and as shown in Fig. 1, the rudder blades are arranged so that each will take the air in opposite directions when partly revolved. On the tops of the hubs of the rudders 70, 70^a, 70^b are held cross-arms 71 and 72 so that by swinging circumferentially the ends of the arms the rudders will turn accordingly. To the ends of the cross-arm 71 are held the ends of a belt or cable 73 which is of a length so that its central part extends to the top of the fuselage 10 in proximity to the mechanism 26, and the central part of the belt passes over a pulley, as 74, adapted to be revolvably moved by a suitable handle, as 75. To the ends of the cross-arm 72 are held the ends of a belt or cable 76 of a length so that its central part also extends to the top of the fuselage 10 in proximity to the mechanism 26, and this central part of the belt is disposed over a pulley 77 adapted to be revolvably adjusted by a second handle 78. When it is desired to steer the machine to the right the handle 75 may be turned to cause the belt 73 to swing the arm 71 so that the rudder 67 will revolve for its blades to take the air, and when it is desired to steer the machine to the left the handle 78 may be turned to cause the belt 76 to swing the arm 72 so that the rudder 68 will revolve for its blades to take the air. Thus I provide a simple and efficient flying machine of a type adapted to be operated so that it will rise directly or rise on such an incline from its landing that the necessity

for causing it to travel a distance on the landing and then taking a gradual climb will be overcome.

In the foregoing description, I have embodied the preferred form of my invention, but I do not wish to be understood as limiting myself thereto, as I am aware that modifications may be made therein without departing from the principle or sacrificing any 10 of the advantages of this invention, therefore I reserve to myself the right to make such changes as fairly fall within the scope thereof.

Having thus described my invention, I 15 claim as new and desire to secure by Letters Patent:—

1. The combination with a flying machine having an engine in its fuselage, of revolvable propellers on the machine for raising 20 the machine from its landing, pairs of propellers rotatable on the machine for driving the machine forwardly, a rotatable propeller on the machine for driving the machine rearwardly, and mechanism having separately 25 operative parts adapted to be operated by the engine and controlling means for said parts whereby the raising propellers will first be driven at a high speed and then at a reduced speed in unison with the propellers 30 for driving the machine forwardly, and subsequently the forwardly driving propellers may be stopped and the propellers for driving the machine backwardly may be operated jointly with the operation of the raising 35 propellers.

2. The combination with a flying machine having an engine in its fuselage, of revolvable propellers on the machine for raising the machine from its landing, pairs of propellers rotatable on the machine for driving the machine forwardly, a rotatable propeller on the machine for driving the machine rearwardly, mechanism having separately operative parts adapted to be operated by the 40 engine, and controlling means for said parts whereby the raising propellers will first be driven at a high speed, then at a reduced speed in unison with the propellers for driving the machine forwardly, after which the 45 forwardly driving propellers may be stopped and the propellers for driving the machine backwardly may be operated jointly with the operation of the raising propellers, and an 50 adjustable controller for shifting the operation of the part of the mechanism which drives the forwardly driving propellers with the other parts of the mechanism.

3. The combination with a flying machine having an engine, of revolvable propellers on the machine for raising the machine from its landing, pairs of propellers rotatable on the machine for driving the machine forwardly, gearing adapted to be driven by the engine, gearing adapted to be driven for driving the 60 propellers to raise the machine, and gearing 65

adapted to be driven by the gearing for first driving the raising propellers at a high speed and afterward the propellers for driving the machine forwardly as well as causing the speed of the raising propellers simultaneously to be reduced. 70

4. The combination with a flying machine having an engine, of revolvable propellers on the machine for raising the machine from its landing, pairs of propellers rotatable on the machine for driving the machine forwardly, gearing adapted to be driven by the engine, gearing adapted to be driven for driving the propellers to raise the machine, shiftable gearing adapted to be driven by the 75 gearing driven by the engine for first driving the raising propellers at a high speed and afterward the propellers for driving the machine forwardly as well as simultaneously causing the speed of the raising propellers 80 to be reduced, and a movable controller for adjusting the shiftable gearing with the gearing driven by the engine. 85

5. The combination with a flying machine having an engine, of revolvable propellers on the machine for raising the machine from its landing, pairs of propellers rotatable on the machine for driving the machine forwardly, a rotatable propeller on the machine for driving the machine rearwardly, gearing adapted to be driven by the engine, gearing adapted to be driven for driving the propellers to raise the machine, mechanism operable by the gearing driven by the engine for driving the propellers to cause forward 90 travel of the machine, means also operable by the gearing driven by the engine for driving the rearwardly acting propeller, and shiftable gearing associated with the gearing for driving the raising propellers, 95 adapted to be first moved to cause the power from the engine to be transmitted to the gearing for driving the raising propellers, then afterward moved to cause the power of the engine to be transmitted to the mechanism for driving the propellers to drive the machine forwardly as well as maintaining rotation of the raising propellers at a reduced speed and subsequently moved for cutting-out of operation said mechanism and 100 causing the power of the engine to be transmitted to the propeller for driving the machine backwardly. 110

6. The combination with a flying machine having an engine, of revolvable propellers on the machine for raising the machine from its landing, pairs of propellers rotatable on the machine for driving the machine forwardly, a rotatable propeller on the machine for driving the machine rearwardly, gearing adapted to be driven by the engine, gearing adapted to be driven for driving the propellers to raise the machine, mechanism operable by the gearing driven by the engine for driving the propellers to cause forward 115 120 125 130

travel of the machine, means also operable associated with the gearing for driving the raising propellers, adapted to be first moved by the gearing driven by the engine for driving the propeller to cause backward travel of the machine, shiftable gearing associated with the gearing for driving the raising propellers, adapted to be first moved to cause the power from the engine to be transmitted to the gearing for driving the raising propellers and then afterward moved 70 to cause the power of the engine to be transmitted to the mechanism for driving the propellers to drive the machine forwardly as well as maintaining rotation of the raising propellers at a reduced speed and pairs of 75 propellers at the rear of the machine, adapted to be separately adjusted rotatably for steering the machine to the right and to the left.

10 cause the power of the engine to be transmitted to the mechanism for driving the propellers to drive the machine forwardly as well as maintaining rotation of the raising propellers at a reduced speed and subsequently moved for cutting-out of operation 80 said mechanism and causing the power of the engine to be transmitted to the propeller for driving the machine backwardly, and a lever associated with the shiftable gearing, 15 adapted to be moved for adjusting this gearing to cut-in and cut-out of coaction the mechanism for driving the propellers which drive the machine forwardly and for cutting-in and cutting-out the coaction of the 20 shiftable gearing with the means for driving the propeller which drives the machine rearwardly.

7. The combination with a flying machine having an engine, of revolvable propellers 30 on the machine for raising the machine from its landing, pairs of propellers rotatable on the machine for driving the machine forwardly, gearing adapted to be driven by the engine, gearing adapted to be driven for driving the propellers to raise the machine, mechanism operable by the gearing driven by the engine for driving the propellers to cause forward travel of the machine, shiftable gearing associated with the gearing for 35 driving the raising propellers, adapted to be first moved to cause the power from the engine to be transmitted to the gearing for driving the raising propellers, then afterward moved to cause the power of the engine to be transmitted to the mechanism for driving the propellers to drive the machine forwardly as well as maintaining rotation of the 40 raising propellers at a reduced speed and subsequently moved for cutting-out of operation said mechanism and causing the power of the engine to be transmitted to the propeller for driving the machine backwardly, and pairs of propellers at the rear 45 of the machine, adapted to be separately adjusted rotatably for steering the machine to the right and to the left.

45 8. The combination with a flying machine having an engine, of revolvable propellers on the machine for raising the machine from its landing, pairs of propellers rotatable on the machine for driving the machine forwardly, 50 gearing adapted to be driven by the engine, gearing adapted to be driven for driving the propellers to raise the machine, mechanism operable by the gearing driven by the engine for driving the propellers to cause forward 55 travel of the machine, shiftable gearing as- 55 associated with the gearing for driving the raising propellers, adapted to be first moved to cause the power from the engine to be transmitted to the gearing for driving the raising propellers and then afterward moved 70 to cause the power of the engine to be transmitted to the mechanism for driving the propellers to drive the machine forwardly as well as maintaining rotation of the raising propellers at a reduced speed and pairs of 75 propellers at the rear of the machine, adapted to be separately adjusted rotatably for steering the machine to the right and to the left.

9. The combination with a flying machine 80 having an engine, of revolvable propellers on the machine for raising the machine from its landing, pairs of propellers rotatable on the machine for driving the machine forwardly, a rotatable propeller on the machine for 85 driving the machine rearwardly, gearing adapted to be driven by the engine, gearing adapted to be driven for driving the propellers to raise the machine, mechanism operable by the gearing driven by the engine for driving the propellers to cause forward travel of the machine, means also operable by the gearing driven by the engine for driving the propeller to cause back- 90 ward travel of the machine, shiftable gearing associated with the gearing for driving the raising propellers, adapted to be first moved to cause the power from the engine to be transmitted to the gearing for driving the raising propellers, then afterward 95 moved to cause the power of the engine to be transmitted to the mechanism for driving the propellers to drive the machine forwardly as well as maintaining rotation of the 100 raising propellers at a reduced speed and subsequently moved for cutting-out of operation said mechanism and causing the power of the engine to be transmitted to the propeller for driving the machine backwardly, and pairs of propellers at the rear 105 of the machine, adapted to be separately adjusted rotatably for steering the machine to the right and to the left.

10. The combination with a flying machine having an engine, of revolvable propellers on the machine for raising the machine from its landing, pairs of propellers rotatable on the machine for driving the machine forwardly, a rotatable propeller on the machine for driving the machine rear- 110 wardly, gearing adapted to be driven by the engine, gearing adapted to be driven for driving the propellers to raise the machine, mechanism operable by the gearing driven by the engine for driving the propellers to cause forward travel of the machine, means also operable by the gearing driven by the engine for driving the propeller to cause backward travel of the machine, shiftable 115 gearing associated with the gearing for driv- 120 ing the raising propellers, adapted to be first moved to cause the power from the engine to be transmitted to the gearing for driving the raising propellers and then afterward moved to cause the power of the engine to be transmitted to the mechanism for driving the propellers to drive the machine forwardly as well as maintaining rotation of the 125 raising propellers at a reduced speed and subsequently moved for cutting-out of operation said mechanism and causing the power of the engine to be transmitted to the propeller for driving the machine backwardly, and pairs of propellers at the rear 130 of the machine, adapted to be separately adjusted rotatably for steering the machine to the right and to the left.

ing the raising propellers, adapted to be first moved to cause the power from the engine to be transmitted to the gearing for driving the raising propellers, then afterward moved to cause the power of the engine to be transmitted to the mechanism for driving the propellers to drive the machine forwardly as well as maintaining rotation of the raising propellers at a reduced speed and subsequently moved for cutting-out of operation said mechanism and causing the power of the engine to be transmitted to the propeller for driving the machine backwardly, a lever associated with the shiftable gearing adapted to be moved for adjusting this gearing to cut-in and cut-out of coaction the

mechanism for driving the propellers which drive the machine forwardly and for cutting-in and cutting-out the coaction of the shiftable gearing with the means for driving 20 the propeller which drives the machine rearwardly, and pairs of propellers at the rear of the machine, adapted to be separately adjusted rotatably for steering the machine to the right and to the left. 25

This specification signed and witnessed this 7th day of June, A. D. 1921.
